UNITED STATES PATENT OFFICE

2,551,113

LIQUID FEEDING MECHANISM FOR
COMBUSTION CHAMBERS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application February 7, 1948, Serial No. 7,018

1 Claim. (Cl. 60—44)

1

This invention relates to combustion chambers adapted for use in rockets and other propulsion apparatus.

It is the general object of the present invention to provide improved constructions by which two combustion liquids may be fed to a combustion chamber in intersecting sprays and also in parallel adjacent sheets, so that very effective intermingling of the combustion liquids will take place.

The invention further relates to arrangements and combinations of parts which will be hereinafter described and more particularly pointed out in the appended claim.

Preferred forms of the invention are shown in the drawing, in which

Fig. 1 is a partial sectional elevation of a combustion chamber, with one form of the invention embodied therein;

Fig. 2 is a partial perspective view of an annular feeding member;

Fig. 3 is a partial sectional elevation showing the invention applied to a rotating combustion chamber;

Fig. 4 is a partial perspective view of the structure shown in Fig. 3; and

Figs. 5 and 6 are detail sectional views showing additional or modified structure.

Referring to Figs. 1 and 2, the closed end portion of a combustion chamber C is provided with an axial feeding member 10 and an annular feeding member 11. The member 10 is provided with a series of slots 14 which are directed outward or away from the axis, and the member 11 is provided with a series of slots 16 which are directed inward or across the axis.

Liquid oxygen under pressure may be supplied to the member 10 through a feed pipe 20, and liquid fuel, as gasoline, may be supplied under pressure to the member 11 through a feed pipe 21.

With this construction, streams or sprays *a* of liquid oxygen will first intersect corresponding streams *b* of gasoline, and will then continue their movement to form a conical sheet of liquid oxygen concentric with and adjacent to a similar conical sheet of gasoline. This accomplishes two very desirable results.

In the first place, the sprays of different liquids intersect and impinge closely adjacent the admission slots 14 and 16 and before the liquids have had a chance to separate into drops. Such drops, if formed, may easily pass each other without impinging or intermingling.

In the second place, the sprays, after passing the area of intersection, continue their move-

2

ments in parallel and adjacent conical sheets or surfaces which present a most favorable opportunity for further and very effective intermingling.

5 In Figs. 3 and 4, the invention is shown as applied to a rotating combustion chamber C' having opposed conical wall portions 30 and 31 and opposed conical casing members 33 and 34 enclosing jacket spaces S and S'. These jacket spaces are closed at their outer ends, as shown at 35 and 36, and are provided with spray openings 37 and 38 which are preferably arranged as spaced rings of elongated slots.

An annular tubular member 40 (Fig. 4) is 15 connected by a series of feed pipes 41 to the jacket space S' through the casing member 34, and a second annular member 44 is similarly connected by pipes 45 to the jacket space S through the casing member 33.

20 Annular baffle plates 47 may be provided to fill in the spaces between the tubular members 40 and 44 and also between said members and the end walls 35 and 36 of the jacket spaces S and S'.

25 The tubular member 40 has two sets of spray openings 50 and 51, and the tubular member 44 has a single set of spray openings 52. One combustion liquid, as gasoline, is supplied under pressure through the jacket space S to the series of slots 37 and also through the pipes 45 and the annular member 44 to the series of slots 52, thus providing two sets of gasoline sprays *g* and *g'*.

30 Liquid oxygen under pressure is supplied through the jacket space S' to one series of spray openings 38 and also through the pipes 41 and the annular member 40 to the two series of spray openings 50 and 51, thus providing three sets of oxygen sprays *x*.

35 With this arrangement, the sprays of each liquid will intersect sprays of the other liquid closely adjacent the spray openings, and all sprays will continue their travel in closely adjacent parallel sheets of contrasting liquids.

40 A rotating combustion chamber of this general type is shown in the prior Goddard application Ser. #507,416, filed October 23, 1943, now Patent No. 2,479,829.

45 As shown in Fig. 4, the gasoline sprays *g'* will extend parallel to and adjacent one set of oxygen sprays *x*, and the gasoline sprays *g* will extend parallel, adjacent and between two sets of oxygen sprays *x*. Very effective intermingling of the combustion liquids is thus accomplished.

50 The sprays may be broken up into eddies for

more effective intermingling on impact by providing a fine coil of wire 60 (Fig. 5) just inside of the spray openings or slots 61 in a feeding member 62, or by providing a strip of very fine wire cloth 70 just inside the spray openings 71 in a feeding member 72, as shown in Fig. 6. It will be understood that the coil 60 or wire cloth 70 may be used in connection with any of the feeding slots or openings previously described.

With either of the described constructions, most effective intermingling of two combustion liquids is very satisfactorily accomplished.

Having thus described the invention and the advantages thereof, it will be understood that the invention is not to be limited to the details herein disclosed, otherwise than as set forth in the claim, but what is claimed is:

A combustion chamber having jacketed wall portions spaced apart at their closed inner ends and adapted to contain liquids under pressure, a pair of parallel annular spray pipes mounted between said closed ends, and tubular means to connect each wall portion at its closed end with the more remote spray pipe, said closed ends and spray pipes having five sets of spray openings through which jets of liquid are ejected, the sets of spray openings in the closed ends of the spaced

5

wall portions being directed at oppositely-inclined angles so that the two series of jets delivered from said openings converge relative to the axis of said chamber and to each other, each annular supply pipe having one set of spray openings directed substantially parallel to the jets delivered from the spray openings in its adjacent wall portion, and one annular supply pipe having an additional set of spray openings which are oppositely inclined with respect to its first set of spray openings therein, whereby jets ejected from each set of spray openings cross jets from a second set of spray openings and continue substantially parallel to jets from a third set of spray openings.

ESTHER C. GODDARD,
*Executrix of the Last Will and Testament of
Robert H. Goddard, Deceased.*
